UNITED STATES PATENT OFFICE.

WILLIAM E. HARRIS, OF NEW YORK, N. Y.

ORE GRINDING AND AMALGAMATING MACHINE.

SPECIFICATION forming part of Letters Patent No. 259,011, dated June 6, 1882.

Application filed September 28, 1881. (No model.)

To all whom it may concern:

Be it known that I, WILLIAM E. HARRIS, of the city, county, and State of New York, have invented a new and useful Improvement 5 in Ore Grinding and Amalgamating Machines, of which the following is a full, clear, and exact specification.

Reference is to be had to the accompanying drawings, forming part of this specification, in 10 which similar letters of reference indicate corresponding parts in all the figures.

Figure 1 is a plan view of a part of my improvement, the driving-pulley being removed. Fig. 2 is a sectional side elevation of the same, 15 taken through the line $\alpha\alpha$, Fig. 1.

The object of this invention is to facilitate the grinding and amalgamating of ores.

The invention consists in the combination, with the grinding-plates, the ring grinding- 20 plates, and the trough, of copper plates, whereby the ore will be finely ground and thoroughly amalgamated, as will be hereinafter fully described.

A represents the frame of the machine. 25 To the upper part of the frame A is attached a bearing, B, in which revolves a vertical shaft, H.

To the upper end of the shaft H is attached a pulley, D, to receive the driving-belt.

30 To the lower end of the vertical shaft H is keyed or otherwise secured the upper grinding-plate, J, which is strengthened by a plate, K, bolted to its upper side, as shown in Fig. 2.

To the upper side of the plate K is attached 35 a hopper, L, to receive the ore.

Through the middle parts of the plates K J are formed openings, through which the ore passes into the space between the upper grinding-plate, J, and the lower grinding-plate, M.

40 The lower face of the upper grinding-plate, J, is made conical, as shown in Fig. 2, and has angular or V-shaped grooves N formed in it to serve as a dress for crushing or breaking the ore. The face of the lower or stationary

45 grinding-plate, M, has radial grooves or slots O formed in it, to operate in connection with the V-shaped grooves N in crushing the ore.

The lower grinding-plate, M, is bolted to a 50 strengthening-plate, P, which is bolted to a ring-flange formed around the upper inner edge of the ring-trough Q.

Upon the upper side of the strengthening-plate K are formed radial ribs R, the ends of which project beyond the edge of the said plate K, and have holes formed through them 55 to receive the upper ends of the spindles a. The lower ends of the spindles a pass through and serve as journals for the ring-plates S, placed within the trough Q, and resting upon the lining-plates T, attached to the bottom of 60 the said trough Q. In the upper sides of the lining-plates T are formed longitudinal grooves b, to serve as a dress, in connection with the ring-plates S, for grinding the ore. To the inner surface of the outer sides of the trough 65 Q are bolted lining-plates U, against which the outer sides of the ring-plates S work. The trough Q is securely bolted to the frame A.

Through a screw-hole in the center of the strengthening-plate P passes a hand-screw, V, 70 upon the upper end of which rests and revolves the lower end of the upright shaft H, that carries the upper grinding-plate, J, so that the said upper grinding-plate, J, can be adjusted at any desired distance from the lower grinding-plate, M, as the character of the ore may 75 require. The hand-screw V is provided with a jam-nut, W, for locking it in place when adjusted.

With this construction, as the ore is fed into 80 the hopper L it passes into the space between the grinding-plates J M and is crushed. As the ore is crushed it is fed outward by centrifugal force, and escapes at the outer edges of the grinding-plates J M into the trough Q, 85 where it is further ground and pulverized between the ring grinding-plates S and the lining-plates T U, attached to the said trough Q, about all of which there is nothing new, the same being shown in a pending application. 90

When the machine is used for amalgamating, a copper plate, c, is attached to the ends of the ribs R, and is made of such a width that its lower edge will be at a little distance from the upper sides of the ring-plates S. A 95 copper plate, d, is also attached to the inner surface of the outer wall of the trough Q, the said copper plate d being made of such a breadth as to extend from the upper edge of the said outer wall of the trough Q to the upper edge of the lining-plate U.

In amalgamating ore, ground pulp is fed into

the hopper L, in connection with a sufficient quantity of water to carry off the tailings from the amalgamator. A quantity of quicksilver—say about ten pounds—is put into the trough Q, and the upper grinding-plate, J, is revolved at a speed of not more than thirty revolutions a minute. The pulp, as it escapes from the grinding-plates J M, will pass down along the inner side of the copper plate c into the ring grinding-plates S, and will be ground very fine, on account of the slow flow of water allowing the heavier particles to settle and be ground, the slow flow of water and the slow revolution of the said ring grinding-plates S causing only very fine particles to be raised and carried off by the water. This slow grinding thoroughly mixes the particles of ore with the quicksilver, so that all the gold and silver will be taken up by the quicksilver, quicksil-

ver being added occasionally until the trough 20 contains about one hundred pounds.

I am aware that it is not broadly new to subject the mercury and pulp to centrifugal action to increase the action of gravity, and I therefore do not claim such; but 25

What I do claim, and desire to secure by Letters Patent, is—

In an ore grinding and amalgamating machine, the combination, with the grinding-plates J M, the ring grinding-plates S, and the 30 trough Q, of the copper plates c d, substantially as herein shown and described, whereby the ore will be finely ground and thoroughly amalgamated, as set forth.

WILLIAM EDWARD HARRIS.
